UNITED STATES PATENT OFFICE.

JOHN K. ROSKAMP, OF GRUNDY CENTER, IOWA.

OAT-HULLING MACHINE.

Application filed September 18, 1925. Serial No. 57,124.

My device relates to improvements in grain hulling machines, and the object of my improvements is to provide a mechanism for hulling oats or other grain having adherent husks or hulls, and for separating the detached hulls from the hulled grain and then diverting the hulls and the grain to different outlets for separated deposit.

This object has been accomplished by the means which are hereinafter described and claimed, it being understood that various modifications may be effected in the elements of my machine without departing from the principles of said invention.

Fig. 1 is a vertical longitudinal and central section of my improved grain hulling machine. Fig. 2 is a transverse section of the convoluted tubular hulling means taken on the broken line 2—2 of said Fig. 1. Fig. 3 is an elevation of one face of said hulling means taken on the broken line 3—3 of Fig. 1 and showing the connected beater elements and the fan. Fig. 4 is a side elevation of the parts shown in Fig. 3.

Oats and some other grain have closely adherent hulls or husks, which are difficult to remove cleanly in a short time, and it is my object to effect this by my machine.

A hollow housing 1 is rigidly mounted on connected divergent legs which constitute a supporting frame 2. The housing has at its forward end an aperture 4 through which may be passed the diminished lower part of spout of a hopper 5 for the unhulled grain. A rotatable shaft 6 is also passed into said aperture 4 and is mounted in bearing-boxes 7 on a bracket 10, both the bracket and hopper being mounted on the housing but may be otherwise supported. A pulley 8 is fixed on the outer extremity of the shaft 6 to carry a driving-belt 9.

The housing 1 is diminished cylindrically at 3 and has a frustal delivery end 22. The part 3 has a longitudinal aperture 25 along its downwardly bulged bottom.

Within the forward end of the housing 1 a centrifugal hulling device 15 is fixed on the shaft 6, and has a forwardly opening cylindrical element 17 open in front and closed in the rear and into apertures of which the spout of the hopper 5 delivers into a plurality of radially arranged tubes opening at one end into the cylinder 17 said tubes having their outer ends opening close to the inner wall of the housing. Each tube is bent at two opposite sides to provide con-

volutions in its inner passage 12 produced by the inner and staggered angles 13, salient and reentrant, along their lengths. A bar 14 is connected diagonally between the outer ends of each abutting pair of tubes 15, extending from one face forward of one to the other face back of the other. A flat ring 18 is fixed upon the rear faces of the tubes 15 concentric with the shaft 6 and carries upon its circumferential periphery a plurality of spaced radial projections or beaters 19. A fan wheel 20 is also fixed upon the shaft 6 within said ring 18. Another ring element 11 is mounted upon the inner wall of the housing 1 partially about the hulling device and partially projecting rearwardly therefrom as far as the separating chamber 3 of the housing. This ring element is corrugated obliquely to supply wide grooves or troughs delivering into the chamber part 3. The ring 11 is shaped with annular narrowing part 26 which projects inwardly nearly to the outer edges of the beaters 19.

A funnel 23 is fixed on a hanger within the housing parts 1 and 3 to open its receiving end adjacent the fan 20 to receive most of the draft therefrom and conduct it into its diminished bend 24 to deliver just above the slotted longitudinal aperture or delivery outlet 25 for the cleansed grain located in a downward bulge of the chamber bottom 3. To the rear of the funnel a sloping plate or baffle device 27 is supported in the chamber 3 anterior to its chaff delivery part 22. The front wall of the housing 1 has an air-inlet aperture 28.

Operation.—Grain is delivered by the hopper 5 into the inner ends of the rotating tubes 15, whence by centrifugal force it is hurled outwardly to pass the tubular convoluted bores with contacts against the angles 13 thereof. This hulls away the husks of the oats from the grain, so that the mixture of both is delivered outwardly against the corrugated ring 11. The air draft aids in drawing this mixture across the path of rotation of the beaters 19 which flail it and the hulls are further crowded and stripped between the beaters and the ring bulge 26 to thus perfect the process of hulling. The mixture of grain and separated hulls pass along the inclined grooves of the ring element 11 into the separating chamber 3. The tendency of the heavier oats is to fall into the bottom bulge of said chamber while the lighter hulls rise through

the upper part of the chamber and pass back of the funnel 23 against the inclined baffling-plate 27, the latter arresting any of the grain which may be with the flying hulls to drop down and slide to the outlet 25, while the hulls pass around the plate and out at the delivery end 22.

The air draft made by the fan, which latter together with the hulling device rotate at about eighteen hundred revolutions per minute, in moving downwardly through the spout 24 of the funnel 23 blows still adherent particles of hulls from the grain below it, the hulls arising to pass out at the delivery opening 22, while the now cleaned grain passes out of the aperture 25 into any receptacle placed without to receive it.

The device has been practically used and is effective in completely hulling the grain, separating and separately delivering the cleaned grain and the chaff. This is rapidly effected, and may be made a continuous operation.

Having described my invention, what I claim as new, and desire to secure by Letters Patent, is:

1. In a device of the character described, a housing having an end wall aperture, a rotatable shaft in said housing, a chamber with one closed and one open end mounted on said shaft within the housing, means for delivering unhulled grain into said chamber, radial arms mounted upon the circumferential periphery of said chamber, hollow and in communication therewith, the opposite longitudinal walls of the arms being zigzag, an annular band mounted in the housing rigidly around and spaced slightly from the open outer ends of said arms and annularly crimped beyond the open ends, the housing being elongated beyond said band and having both a terminal and a bottom delivery port, and means for creating an air current lengthwise through said housing to carry separated hulls and grain through the elongated part thereof to said ports respectively as separated in said elongation.

2. In a device of the character described, a housing having an end wall aperture, a rotatable shaft in said housing, hollow zigzag arms mounted radiatingly upon said shaft, means for delivering unhulled grain into the open inner ends of said arms, an annular band around and slightly spaced from said arms, said band being obliquely crimped and extending beyond said arms

away from said apertured end wall, said housing being elongated beyond said band and provided with an upper delivery port for separated hulls and a bottom port for separated grain, and means for creating an air current through said housing lengthwise toward said delivery ports.

3. In a device of the character described, a housing having receiving and delivery openings, and a rotatable huller mounted within the housing having a plurality of tubes spaced apart and which have staggered projections on their inner opposite side walls, the tubes opening to receive centrally and to deliver circumferentially, propeller bars connected diagonally between the outer ends of the tubes, and means for creating an air draft through the housing between the tubes and across their outer ends and said propeller bars.

4. In a device of the character described, a housing having receiving and delivery openings, a rotatable hulling device in said housing having spaced zigzag open end tubes open at both ends, arranged substantially radially to receive centrally of the device and deliver circumferentially, inclined propeller bars fixed between the outer ends of the tubes, and beater elements mounted upon the tubes within the path of movement of material ejected from the tubes as propelled in one direction by said propeller bars.

5. In a device of the character described, a housing having receiving and delivery openings, a rotatable hulling device in said housing having convoluted passages to receive unhulled grain and deliver it circumferentially to be hulled by contacts of the grain therein with the convolutions of the passages, fan vanes fixed on said device and oblique circumferential bars fixed on the device to propel ejected grain and separated hulls into the path of rotation of the beater elements, a ring element surrounding said hulling device and projecting therebeyond and having an integral inwardly projecting annulus abutting the outer edges of the beater elements, said ring element being corrugated inclinedly transversely, and a fan rotatable to drive an air current across the hulling device and said propeller and beater elements.

In testimony whereof I affix my signature.

JOHN K. ROSKAMP.
